GRAPPLING DEVICE

Malcolm G. Murray, Ellwood City, and Rodney W. Porter, Zelienople, Pa.

Application January 13, 1948, Serial No. 2,028

5 Claims. (Cl. 294—106)

1

This invention relates to a grappling device for handling objects and more particularly to such a device for handling elongated tubes and the like.

During the processing of certain materials it is sometimes necessary to move the material from one stage of processing to another. A lift hoist or similar device is usually employed to accomplish such movement. Little difficulty is encountered when the material to be transferred can be easily reached and is of such a nature that it can be readily engaged by the lift hoist by relatively simple means, such as a chain sling, hook, magnet, cable, etc. Frequently the material to be transferred is in such a location and is of such a nature that its handling cannot be accomplished with facility using the conventional apparatus, for example, the transfer of elongated metal tubes from a coating tank to a baking chamber. Currently this handling is done by hooking a lift hoist to a holder which holds a cluster of tubes suspended vertically. After being withdrawn from the coating dip tank the cluster is attached to a hoist by inserting the hoist hook into a ring which projects from the top of the elevated holder and is thus carried to the bake chamber. When using this method it is necessary for the operator to climb a ladder to the top of the elevated cluster and center the hoist hook so that it will engage the ring member of the holder. When the cluster is carried in this manner there is created the added danger of detachment of the holder from the hoist hook if the cluster strikes an obstruction. This is, of course, unsafe and undesirable.

An object of our invention is to provide a grappling device for handling objects that is simple and rugged in construction.

Another object of our invention is to provide such a device that can be attached to a load from a remote position.

It is another object of our invention to provide such a device that cannot be accidentally disengaged once it is attached to a load.

Still another object of our invention is to provide such a grappling device that will be relatively simple to operate in a safe, foolproof manner.

These and other objects will become more apparent after referring to the following specification and attached drawings, in which:

Figure 1 is a side view of apparatus embodying the grappling device of our invention;

Figure 2 is a partial plan view of the apparatus;

Figure 3 is a sectional view on line III—III of Figure 2; and

2

Figure 4 is a view similar to Figure 3 showing the pin depressed and the finger member disengaged.

Referring more particularly to the drawings, reference numeral 2 indicates a cone-shaped member rigidly attached to a holder 4 from which a number of tubes are suspended vertically. The tube cluster is shown in Figure 1 being withdrawn from the dip tank 8 by means of elevator 10 which is operated by means of cables 12. Hoist 14, operated by control buttons 16 at the end of control cable 17, is mounted on tramrail 18. Suspended from hoist 14 is a vertically slotted bell-shaped member 20. The inner surface 22 of bell-shaped member 20 slopes at an angle of approximately 60 degrees with respect to the horizontal plane thereof and is adapted to fit slidingly over the corresponding outer surface 24 of cone member 2 which surface also slopes at an angle of approximately 60 degrees with respect to the same horizontal plane. Vertically extending hook-shaped finger members 26 are pivotally mounted in the four slots 28 of bell member 20 by means of bearing pins 30 which carry washers 32. The bearing pins 30 are inserted into the openings 34 which are machined in slots 28 and are held in place by cotter pins 36. The finger members 26 have hook-ends 38 which are inclined upwardly, preferably at an angle of 15 degrees, and are adapted to fit into groove 40 around the base of cone member 2. The upper surface 42 of groove 40 is undercut preferably at a similar angle 44 of approximately 15 degrees to insure a secure hold for the hook-ends 38. A bolt 48 is inserted through the hole 46 in the top of bell member 20 with its head below the inside upper surface of bell member 20 and its shaft 54 extending upwardly therefrom. Mounted around the shaft 54 adjacent its upper end is an internally screw-threaded trunnion member 50 with lugs 52 projecting therefrom for attaching to the pulley of hoist 14. Resting in a slight concavity in the inside upper surface of the bell member 20 and around the shaft 54 of bolt 48 adjacent its head is a thrust bearing 56. A cylindrical spacing bushing 58 is provided around the extending shaft 54 intermediate the trunnion member 50 and the outer top surface 60 of bell member 20. Trunnion 50 is held in position by means of a cotter pin 62, which passes through aligned openings in the sides of trunnion 50 and shaft 54. The head portion of each finger member 26 is designed with a lug 64 projecting inwardly therefrom. When mounted, the lugs 64 are positioned subjacent to the holes 66 which are machined through the top of the bell member 20. An annu-

lar plate 68 is centered around bushing 58 above bell member 20. Fixed in plate 68 and extending therefrom into holes 66 are four release rods 70 whose lengths are sufficient to depress the lugs 64 and thereby pivot the finger members outwardly when plate 68 is depressed.

The device of our invention is shown in Figure 1 in position for hooking up a tube holder 4 used in the resinous coating of the tubes which are suspended from holder 4. The tube cluster 6 is lowered into the dipping tank 8 by means of the overhead traveling hoist 14. The hoist 14 is then unhooked and the holder 4 and the cluster 6 which it holds are lifted out of the dipping tank 8 at a relatively slow uniform speed by means of an elevator 10 until the tubes are completely withdrawn. It is then necessary to attach the hoist 14 again in order to move the tube cluster 6 laterally so that it may be lowered into an adjacent baking oven (not shown). Our invention permits this attachment to be readily accomplished from the floor by lowering the bell member 20 until it locks on the cone member 2. With the conventional hook it would be necessary for the operator to climb a ladder in order to effect the hook up. It is unsatisfactory to allow the tubes to remain hooked up while they are being raised by the elevator 10 as the slack cable does not follow the grooves of hoist 14 and is, therefore, subject to uneven wear.

In operation, after the tube cluster 6 is raised from the dip tank 8 by means of the elevator 10, the hoist 14 lowers the bell member 20 to engage cone member 2. When the bell member 20 is lowered on the cone 2, the hook-ends 38 of finger members 26 slide along the sloping surface 24, swinging out as required, until they reach the groove 40 where they swing inwardly by gravity. When the bell member 20 is raised from its lowest position, the hook-ends 38 engage the undercut surface 42 of the groove 40 and the load is then in a position to be carried. The undercut of surface 42 prevents disengagement of the fingers while a load is being held suspended.

When the load has been transferred to its destination and is at rest, in the bake oven below the surface of the mill floor, the bell member may be released by lowering it to its lowest position and depressing the annular plate 68 by hand or by any other suitable means. This causes the rods 70 to bear down on lugs 64 which forces the fingers 26 to swing outwardly until the hook-ends clear the cone 2. While the fingers are in this position, the bell member 20 is hoisted out of contact with the cone member 2 and the release is completed. The finger members 26 swing back to the original hanging position shown in Figure 3 as soon as the pressure on the release rods 70 is removed.

While one embodiment of our invention has been shown and described, it will be apparent that other adaptations and modifications may be made without departing from the scope of the following claims.

We claim:

1. A grappling device for handling objects comprising a bell-shaped member having vertical slots and adapted to be carried by a lifting hoist, a plurality of vertically extending finger members having inwardly extending hook-ends pivotally mounted in the slots of said bell member, lugs projecting inwardly from the head portions of said finger members, a cone member for supporting the objects to be handled, said cone member adapted to fit within said bell-shaped member, the cone member having a groove around

its base to receive the hook-ends of said finger members, and positive means for engaging said lugs to disengage said hook-ends from the groove in said cone member.

5 2. A grappling device for handling objects comprising a bell-shaped member having vertical slots and adapted to be carried by a lifting hoist, a plurality of vertically extending finger members having inwardly extending hook-ends pivotally mounted in the slots of said bell member, lugs projecting inwardly from the head portions of said finger members, a cone member adapted to be attached to the objects to be handled, said cone member adapted to fit within said bell-shaped member, the cone member having a groove around its base to receive the hook-ends of said finger members, and means for disengaging said hook-ends from the groove in said cone member, said means consisting of a plurality of vertical release rods extending downwardly through holes in the top of said bell member to said lugs, and a plate member above said bell member for depressing said release rods.

20 3. A grappling device for handling objects comprising a bell-shaped member having vertical slots and adapted to be carried by a lifting hoist, a plurality of vertically extending finger members having inwardly extending hook-ends pivotally mounted in the slots of said bell member, lugs 25 projecting inwardly from the head portions of said finger members, a cone member adapted to be attached to the objects to be handled, said cone member adapted to fit within said bell-shaped member, the cone member having a groove around its base to receive the hook-ends of said finger members, and means for disengaging said hook-ends from the groove in said cone member, said means consisting of a plurality of vertical release rods extending downwardly through holes in the top of said bell member to said lugs, and a plate member above said bell member for depressing said release rods.

35 4. A grappling device for handling objects comprising a bell-shaped member having vertical slots and adapted to be carried by a lifting hoist, a plurality of vertically extending finger members having inwardly extending hook-ends pivotally mounted in the slots of said bell member, lugs 40 projecting inwardly from the head portions of said finger members, a cone member adapted to be attached to the objects to be handled, said cone member adapted to fit within said bell-shaped member, the cone member having a groove around its base to receive the hook-ends of said finger members, the upper surface of said groove being undercut, the upper surfaces of the hook-ends of said finger members being inclined upwardly, and positive means for engaging said lugs to disengage said hook-ends from the groove in said cone member.

45 5. A grappling device for handling objects comprising a bell-shaped member having vertical slots and adapted to be carried by a lifting hoist, a plurality of vertically extending finger members having inwardly extending hook-ends pivotally mounted in the slots of said bell member, lugs projecting inwardly from the head portions of said finger members, a cone member adapted to be attached to the objects to be handled, said cone member adapted to fit within said bell-shaped member, the cone member having a groove around its base to receive the hook-ends of said finger members, the upper surface of said groove being undercut, the upper surfaces of the hook-ends of said finger members being inclined upwardly, and means for disengaging said hook-ends from the groove in said cone member, said means consisting of a plurality of vertical release rods extending downwardly through holes in the top of said bell member to said lugs, and a plate member above said bell member for depressing said release rods.

55 6. A grappling device for handling objects comprising a bell-shaped member having vertical slots and adapted to be carried by a lifting hoist, the inner side surfaces of said bell member having an angle of slope of approximately 60 degrees, a plurality of vertically extending finger members having inwardly extending hook-ends pivotally mounted in the slots of said bell member, lugs projecting inwardly from the head portions of said finger members, a cone member adapted to be attached to objects to be handled, said cone member adapted to fit within said bell-shaped member, the outer surfaces of said cone member

having an angle of slope of approximately 60 degrees to conform with the angle of slope of the inner side surfaces of said bell member, said cone member having a groove around its base to receive the hook-ends of said finger members, the 5 upper surface of said groove being undercut, the upper surfaces of the hook-ends of said finger members being inclined upwardly, means for disengaging said hook-ends from said groove in the cone member, said means consisting of a plurality 10 of vertical release rods extending downwardly through holes in the top of said bell member to

said lugs, and a plate member above said bell member for depressing said release rods.
